UNITED STATES PATENT OFFICE.

THOMAS S. FOX, OF BROOKLYN, NEW YORK.

PRINTING.

1,420,086.

Specification of Letters Patent. Patented June 20, 1922.

No Drawing.

Application filed August 22, 1919. Serial No. 319,261.

To all whom it may concern:

Be it known that I, THOMAS S. FOX, a citizen of the United States, residing at Brooklyn, in the county of Kings and State 5 of New York, have invented certain new and useful Improvements in Printing, of which the following is a specification.

My invention relates to improvements in printing, and in one of its preferred applications has reference to a method or process for the breaking of or relieving the heavier or solid color effects such as usually appear in backgrounds or shadings. In solid backgrounds, the effect is too intense and the 10 solid color frequently smudges or smears off. For the purpose of overcoming this is a common practice to engrave by hand the part of the cut which otherwise would print in solid color and this engraving relieves 15 the background or shading effects and reduces this liability of smudging and smearing.

The carrying out of my invention contemplates a new and useful use of printing films, special inks, etc., in the treatment of printing plates of metal, stone, etc. The use of transparent printing mediums such as films is described in the patent to Benjamin Day 214493 of 1879, but in the use of 20 printing films it has been found difficult and impractical to print even effects with films the printing elevations or surfaces of which occupy a large part, say $\frac{1}{2}$ of the total area of the film surface while it is easy to make 25 impressions with films where say only $\frac{1}{8}$ more or less of the total area of the film surface is covered by the printing elevations.

In order to get dark printing effects by 30 films or etching, I make my film impressions with a film that carries little color, that is to say, films, the printing elevations or surfaces of which occupy a comparatively small area. I use on my film an ink insoluble in one solvent and then apply another 35 ink in a manner hereinafter described soluble in another solvent over the impressions of the first ink and over the intervening places, after which I dissolve away the first 40 ink impressions with their solvent leaving the second application of ink, which will then represent a heavy dark printing surface covering the places which were left bare between the first impressions. I have thus reversed my film impressions. What was 45 black ink is now exposed metal and what 50

was bare is covered with ink. In the practice of my process I prefer to proceed substantially as follows: I may use a roller preferably of rubber charged with an ink which may be soluble in alcohol or other 55 solvents, but preferably soluble in water. This ink may be made up by mixing 1 oz. of honey to $\frac{1}{4}$ oz. of glycerine with an equal amount by weight of graphite in the wet state known in the market as Atcheson's 60 concentrated graphite or aquadag, sufficiently freed from water. Similar inks may be made of water soluble substances such as fish glue, gums, etc., with any suitable coloring matter such as lamp black, etc. 70

I proceed to ink my film by rolling the film being preferably water proof as more particularly set forth in my Patent 761668 of 1904 and in turn transfer or print these 75 water soluble impressions or marks upon the surface to be treated. I may then dust upon these impressions or marks any suitable powder, but preferably a water soluble powdered gum such as gum arabic, which will unite with the ink, owing to the moisture remaining in the same, forming a firm 80 surface or crust which will not smudge. A moist vapor such as the breath, or otherwise will facilitate this and is preferably applied only after all surplus powder has 85 been removed preferably by brushing. I may then roll or apply by dauber or pad, but preferably by rolling with the pliable roller, an acid resisting ink over the entire 90 surface which of course covers the water soluble ink and surrounding parts of the plate with a film of ink sufficiently thin and yet porous enough to allow water which is 95 then applied to reach the gum covered impressions to dissolve them, carrying away also any of the acid resisting ink upon their 100 surface, leaving the surface bare where the water soluble ink was first applied and the metal now covered with an acid resisting ink where it was formerly bare. The plate 105 is now ready for treatment or etching in any well known manner.

After making impressions with the water soluble ink as above described, I may at any stage of the operation stop out any selected 110 portions by painting over the same with substance such as asphaltum or the like soluble in benzole, etc., and then after re-inking the film I may shift the same and continue to make more impressions on the 115

places not stopped out which in turn may be treated with asphaltum and so on. I may now wash off all the asphaltum with benzole which leaves the water ink marks in contact with the metal surface unchanged so that I may now apply my acid resisting ink and proceed as hereinbefore stated.

There are many instances in which this process is useful such as in the treatment of 10 electrotypes with smooth black printing surfaces which for certain reasons it is desirable to relieve with engraved effects as of stippling, lines, etc., which will show in white against a black background, numerous instances of which may be seen in advertising 15 cuts of present day publications, but in which case the effect has been produced by engraving such as with a hand tool. But this hand tooling is a slow and expensive 20 method. In treating such surfaces I may paint or smear in the depressions such as between type or sunken letters, etc., with a quick drying acid resisting varnish and remove same from the surface of the letters 25 with a flat piece of charcoal or emory paper any of the varnish that may have lodged thereon and may then proceed as aforesaid.

It will be observed that by depositing my 30 acid resisting ink by rolling, etc., I am able to regulate the amount I desire to apply and may also apply very evenly as would not be the case in flowing and causing an uneven 35 coating with the liability of becoming too thick in some places to allow a solvent to penetrate to dissolve the impressions underneath.

This process is also of particular utility 40 in other reversing operations. It facilitates the use of printing films on plates for intaglio printing, enabling the artist to see his work in its proper color value, the printing in this case being opposite from typographic printing, in that the printing ink occupies the etched depressions. It is also desirable at 45 times to reverse design film patterns. I may also thin my water soluble ink with water or use other soluble inks and make impressions of dots, lines, etc., with a pen or brush or an equivalent tool in combination with or 50 without film impressions and then apply my said resisting ink or other soluble ink and proceed substantially as previously outlined. I am aware that efforts have been made to 55 accomplish the results I have enumerated by making impressions by an acid resisting ink and dipping or flowing an alcoholic solution over the same but by my method I avoid a running, streaky uneven coating and am able to regulate at will the amount and 60 development of the impressions underneath without the danger of smudging my water soluble impressions. I am also able to treat locally any part of the photographed inked print without danger of using a solvent that

would destroy parts not intended if flowed over the same. I may also make my film impressions with an ink soluble in alcohol such as a resin oil ink known as Cuti Cura manufactured by George H. Morrell 49 Rose St. New York city and using as a dusting 70 powder preferably gum mastic and I may if desired melt this by alcohol fumes to form the crust and then over this I may roll linseed oil varnish ink which is insoluble in alcohol and is known in the trade as 75 Litho #6 made by the same firm and develop my first impressions with alcohol, but I find it simpler and more satisfactory to use my water soluble ink, thus avoiding any danger of solvents that might easily dissolve in 80 parts not intended, the water as a solvent having no effect on acid resisting inks.

Of course it will be understood that various modifications may be made in the ingredients and proportions of the same without departing from the spirit of the invention as claimed, and the same applies as to the particular order or procedure pursued in the practice of my process.

I claim:

1. The process of reversing impressions in printing consisting in the making of said impressions in a water soluble ink, then dusting on powdered material, then rolling on another ink soluble in another solvent and then dissolving away the water soluble ink.

2. The process of reversing impressions in printing consisting in making water soluble printing ink impressions, dusting on a powdered gum soluble in water, then applying moist vapor and then applying another ink soluble in another solvent and dissolving away the water soluble ink.

3. The process of reversing impressions in printing consisting in coating the depressions in a printing surface to be treated with an acid resisting material, making impressions with a material soluble in one solvent, dusting on powdered material, then applying material soluble in another solvent, then dissolving away the first material impressions.

4. The process of reversing impressions in printing consisting in stopping out with a material solvent in one solvent, making impressions with a material soluble in another solvent, dusting powdered material on the same, dissolving away the stopping out material with its solvent, then applying a material over the powdered material impressions and other parts soluble in a different solvent, and then dissolving away the impressions.

5. The process of reversing impressions in printing consisting in making impressions by pen or brush, with a material soluble in one solvent, making film impressions with

a material soluble in the same solvent, dusting on powdered material, then applying material soluble in another solvent, then dissolving away the pen and brush film im-
5 pressions.

6. The process of reversing impressions in printing consisting in making impressions with a material soluble in one solvent, applying gum mastic thereto, treating the same
10 with a volatile solvent, applying another ink soluble in a different solvent, and dissolving the inked impressions.

7. The process of reversing impressions in printing consisting in the making of said
15 impressions in a water soluble ink, then applying another material, then rolling on an

ink soluble in another solvent, and dissolving away the water soluble ink.

8. The method of producing a printing surface, consisting in producing upon a sur-
face the subject to be printed, applying marks upon said surface with material soluble in certain solvents, also applying other marks upon said surface by films with material solvent in other solvents, removing some
25 of said marks, subsequently using said surface for the preparation of a printing surface to be used in a press so that the parts uncovered by the removed marks will be
distinguishable in the printed copy.

In testimony I hereunto affix my signature.
THOMAS S. FOX.
